UNITED STATES PATENT OFFICE.

ALBERT B. SCHOFIELD, OF BROOKLYN, NEW YORK.

DESIGN FOR A BUTTON.

SPECIFICATION forming part of Design No. 25,468, dated May 12, 1896.

Application filed March 19, 1896. Serial No. 583,978. Term of patent 3½ years.

To all whom it may concern:

Be it known that I, ALBERT B. SCHOFIELD, of Brooklyn, in the county of Kings and State of New York, have invented and produced a new and original Design for Buttons, of which the following is a specification, reference being had to the accompanying drawing, forming a part thereof.

The leading features of my design consist in a button presenting on its face a shield, a scroll within the margin of the shield, and a field at the top of the shield, the said scroll and field at the top of the shield being differentiated from the shield in color.

In the accompanying drawing the shield, 15 which may be blue in color, is denoted by A; the field above the shield, which may be white in color, is denoted by B, and the scroll on the shield, which may also be white in color, is denoted by C. 20

What I claim is—

The design for a button, substantially as shown.

ALBERT B. SCHOFIELD.
